(57) **CLAIM**

The ornamental design for a tapered cup, as shown and described.

DESCRIPTION

FIG. 1 is a front perspective view of a first embodiment of a tapered cup showing my new design;

FIG. 2 is a front elevation view thereof, the right, left and rear elevation views being the same as the front elevation view;

FIG. 3 is a top plan view thereof;

FIG. 4 is a bottom plan view thereof;

FIG. 5 is a front perspective view of a second embodiment of a tapered cup;

FIG. 6 is a front elevation view of the tapered cup of FIG. 5, the right, left and rear elevation views being substantially the same as the front elevation view;

FIG. 7 is a top plan view of the tapered cup of FIG. 5; and, FIG. 8 is a bottom plan view of the tapered cup of Fig.

The broken lines in the drawings depict portions of the tapered cup that form no part of the claimed design.
